Primary Examiner — Ian Simmons*Assistant Examiner* — Khawaja Anwar*(74) Attorney, Agent, or Firm* — Wegman, Hessler & Vanderburg(57) **CLAIM**

We claim the ornamental design for a lawn care vehicle hood assembly, as shown and described.

DESCRIPTION

FIG. 1 is a top perspective view of a lawn care vehicle hood assembly, shown in typical usage condition, showing our new design;

FIG. 2 is a top perspective view thereof, with environment removed;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof; and,

FIG. 8 is a left side elevation view thereof.

The broken lines shown in the drawings represent unclaimed environment only and form no part of the claimed design.
